INFEED ATTACHMENT FOR CENTERLESS
GRINDING MACHINES

Keith Anderson, Highland Park, Mich.

Application February 26, 1949, Serial No. 78,645

6 Claims. (Cl. 51—103)

1

This invention relates to centerless grinding machines and more particularly to mechanism for controlling and operating the in and out feeding of the carriage which carries the regulating wheel relative to the work piece.

It is the principal object of this invention to provide an infeed attachment for the centerless grinding machine whereby said in and out feeding movements of the carriage are effected automatically.

It is the further object of this invention to provide an infeed nut threadably mounted upon the carriage lead screw for reciprocal rotary movements thereon, said nut being rotatively retained within and with respect to said carriage.

It is the further object of this invention to provide a support for the carriage lead screw which will permit manual rotary movements thereof, which movements will cause corresponding movements in one direction or the other of the aforesaid nut thereby controlling movements of the carriage under such manual control.

It is the further object of this invention to provide a motor driven mechanism for effecting reciprocal arcuate or rotary movements of said infeed nut upon said lead screw to provide for reciprocal in and out feed movements of said carriage and the regulating wheel mounted thereon.

It is the further object of this invention to provide a pair of rotary cams arranged in such timed relation to each other and positioned relative to a reciprocal cross head so as to effect timed reciprocations thereof whereby said carriage is fed inwardly to a predetermined position, retained in this position for a short period, and then withdrawn carrying the regulating wheel therewith to another predetermined position.

It is the still further object of this invention to provide a work piece ejecting mechanism which is associated with and controlled by said infeed attachment whereby said work piece is ejected from its position between the grinding wheel and the regulating wheel as and during the outward feeding of said regulating wheel under control of said attachment.

It is the further object of this invention to provide a pneumatic mechanism controlled by a third cam on said attachment to effect automatic ejection of the work piece in timed relation to the controlled outfeeding movements of said carriage.

It is the still further object of this invention to provide means for regulating the extent of the in and out feeding as well as the speed thereof.

2

These and other objects will be seen from the following specification and claims in conjunction with the appended drawings in which:

Fig. 1 is a front elevational view of the centerless grinding machine with the automatic infeed attachment thereon.

Fig. 2 is a transverse plan view of the mechanism comprising the infeed attachment as associated with the machine carriage which is fragmentarily shown.

Fig. 3 is a right end elevational view of the infeed attachment thereof.

Fig. 4 is a front elevational view thereof as associated with the machine carriage which is fragmentarily shown.

Fig. 5 is an enlarged plan section taken on line 5—5 of Fig. 4; and

Fig. 6 is an elevational section taken on line 6—6 of Fig. 4.

20 It will be understood that the above drawings illustrate merely a preferred embodiment of the invention and that other embodiments are contemplated within the scope of the claims hereinafter set out.

25 Referring to Figure 1 the centerless grinding machine includes the base 1 supporting the bed 2 which carries the stationary grinding wheel housing 3 journalling the abrasive grinding wheel 4.

30 A truing attachment 5 is generally indicated as carried by wheel housing 3 for truing said grinding wheel in a manner which forms no part of the present invention, and for this reason further description of the structure thereof is omitted.

35 It is sufficient to state that the grinding wheel 4 is positioned within housing 3 and centrally secured to the rotary drive shaft 6 which is driven by a suitable electric motor preferably, 40 which motor is not shown in the drawing, as the mechanism for rotating said grinding wheel itself forms no part of the present invention. It is sufficient to state that grinding wheel 4 is adapted for rotation with respect to and in engaging relation with the cylindrical shaped work piece 7.

The aforesaid bed 2 includes the guideways 8 which are arranged at right angles to the axis of the grinding wheel shaft 6 and upon which is mounted the upper slide 9.

45 The upper slide 9 hereafter denoted as the carriage 9 is suitably mounted upon the guideways 8 whereby said carriage is adapted for reciprocal adjustment at right angles to the axis of the work piece 7.

50 Regulating wheel housing 10 is secured to and

carried by carriage 9 at its left end and is adapted to house and journal the rotatable regulating wheel 11 which engages work piece 7 on its side opposite from the grinding wheel 4, said regulating wheel being adapted to maintain said work piece against the surface of said grinding wheel as well as upon its supporting work blade 12 carried by work rest 13.

Said work rest is adjustably mounted upon the transverse guideway 14 on the bed 2 whereby said work rest may be adjusted in a direction transverse to the reciprocal adjustments of the carriage 9.

A suitable rotatable drive shaft 15 is provided upon which the regulating wheel 11 is mounted and secured within its housing 10, there being preferably an electric motor joined to said shaft for operating the same, there being also suitable mechanism for regulating the speed of rotation of the regulating wheel 11 which forms no part of the present invention and consequently its description is omitted. It is sufficient to state for the purpose of the present application that the regulating wheel 11 is power rotated by the shaft 15 which is shown in Figure 1.

A truing attachment generally indicated by the numeral 16 is adjustably mounted upon the regulating wheel housing 10 for truing said regulating wheel 11. As the structure of said truing attachment forms no part of the present invention, its description is omitted with the exception that the truing hand wheel is designated by the numeral 17.

Referring to Figure 1 a bracket 18 is secured to the right end of bed 2 and projects upwardly therefrom to journal and support the lead screw 19 which carries the operating spokes or hand wheel 20 to effect manual rotation of said lead screw.

Collars 21 and 22 are secured to lead screw 19 upon opposite sides of the bracket 18 to effectively retain said lead screw against longitudinal movement relative to said bracket.

As shown in Figures 1, 2, 3 and 6, the other end of said lead screw extends through and is in threaded engagement with the infeed nut 23 which projects into the carriage 9 and is rotatively positioned therein as by the thrust bearing 24. Said bearing is threadably or otherwise secured within carriage 9 and retainingly engages the annular shoulder 25 on the infeed nut 23 so that the latter is rotatively retained with respect thereto.

From the above description it is seen that upon manual rotation in one direction or the other of the lead screw 19 as by its hand wheel 20, the infeed nut, retained against rotation in the manner hereafter set out, is adapted to movements to the right or the left in Figure 1 upon said rotated lead screw.

In view of the connection between the infeed nut 23 and carriage 9 it is seen that such movements of the nut will be transmitted to the carriage 9 so that the same and the regulating wheel 11 can be initially adjusted to the approximate desired position with respect to the grinding wheel 4.

The present invention includes an automatic mechanism now to be described whereby under power operation said infeed nut will be intermittently and reciprocally rocked upon the lead screw 19. Here again, rotary movement of the infeed nut upon said lead screw will cause movements of said nut 23 to the right or to the left upon the stationary lead screw 19 to thereby effect

corresponding movements to the right or to the left of the carriage 9 shown in Figure 1.

Normally there is sufficient inertia as between the reciprocated arcuately moving infeed nut 23 and the lead screw 19 that the latter is relatively stationary. Consequently such reciprocal movements of the infeed nut are adapted to effect progressions to the right or to the left of said nut upon the relatively stationary lead screw 19. To assure that the lead screw 19 will not rotate, a suitable friction clamp may be employed if desired.

Referring to Figure 6 the lead screw nut 23 is shown mounted upon and in threaded engagement with the lead screw 19, the latter being relatively stationary. The hollow clamp 26, split at 27 is adjustably positioned around the infeed nut 23 and effectively secured thereto as by the adjustable bolt 28 which inter-connects the free ends 29 of said clamp.

An extension 30 forms a part of the clamp 26 being arranged diametrically from the free ends 29 thereof, said extension being slotted at 31 to adjustably receive the bolt 32 for swivelly joining one end of the link 33 to said clamp.

As shown in Figure 2 the bolt 32 threadably engages the link 33 and projects through the slot 31 in the clamp 26 and is retained with respect thereto by the nut 34.

The opposite end of the link 33 is joined by a suitable pin 34 to one end of the reciprocal cross head 35. The latter is formed with the bosses 36 oppositely extending therefrom and arranged at its ends, said bosses having circular openings to receive the supporting shafts 37 which respectively extend thru said bosses. By this construction the cross head 35 is adapted for reciprocal sliding movement upon the spaced transverse rods 37.

As shown in the drawings a suitable hollow framework or housing 38 projects from the right end of the carriage 9 and is secured thereto by the bolts 39 as shown in Figure 4. The respective opposite ends of the shafts 37 are nested and secured within the bosses 40 which have central openings to receive said shafts and which bosses form an integral part of the housing 38. Consequently it appears that the housing 38 which supports the reciprocal cross head 35 is mounted and secured upon carriage 9 for movement therewith.

The cross head 35 which is adapted to affect reciprocal rotary movements of the infeed nut 23 thru the interconnecting link 33 has a pair of spaced cam engaging rollers 41 and 42 arranged adjacent the opposite ends of said cross head as illustrated in Figures 2, 3, 4, 5 and 6. Said rollers are intermittently and alternately engaged by the rotatable cams 43 and 44 respectively whereby said cross head is projected to the left as in Figure 6 by the cam 43 and subsequently to the right by the cam 44.

Both of the cams 43 and 44 are mounted upon the cam driving shaft 45, being keyed thereto at 46 for rotation therewith. As shown in Figure 5 the left end of shaft 45 is supported and journalled within the ball bearings 47 supported within the projecting boss 48 forming a part of the housing 38. The right end of cam driving shaft 45 extends over and is suitably secured to rotatable drive shaft 49.

The said shaft 49 extends from the speed reducer 50 which is in the upright position shown in Figure 4, being secured to housing 38 by the bolts 51. Said speed reducer is initially operated

by the driven shaft 52 which projects into said speed reducer and which is suitably interconnected with the drive shaft 49 by a plurality of gears. The particular construction of the speed reducer forms no part of the present invention and consequently further description thereof is omitted.

As shown in Figures 2, 3, 4 and 6 driven shaft 52 is rotated by the pulley wheel 53 driven by the pulley belt 54. Electric motor 55 has a rotatable drive shaft 56 upon which is joined the drive pulley 57. Pulleys 53 and 57 are interconnected by the pulley belt 54 whereby rotary motion is given thru speed reducer 50 to the cam rotating shaft 45.

As shown in Figure 6 cam 43 has a portion between the points *a* and *b* of substantially constant radius, and this extends over an arc of approximately 90 degrees. During the period of engagement of the cam rotating in a counter-clockwise direction it would appear that this portion of the cam between the points *a* and *b* maintains the cross-head 35 in its extreme position to the left as in Figure 6. This corresponds to the infeed position of the carriage 9 at which and during which period the work piece is being ground.

After cam 43 leaves the roller 41 the second cam 44 is now in operative engagement with cross-head operating roller 42 for projecting cross-head 35 in the opposite direction upon its supporting rods 37. And it is this movement of the cross-head which is transmitted to the link 33 which governs the outfeeding of the carriage 9 to permit ejection of the work piece and the insertion of a new work piece upon the work blade 12 between the grinding wheel 4 and the regulating wheel 11.

At the same time as the cam 44 begins its effective engagement with the roller 42 initiating the outward feed movement of the carriage, a third cam 58 is brought into operative position to energize a pneumatic work piece ejecting mechanism, to clear the work blade 12 and to provide for the insertion of the new work piece thereon.

More particularly as shown in Figures 2, 3 and 4, this cam 58 is secured upon the cam driving shaft 45 by the locking bolt 59, Figure 4, for rotation with said shaft. Said cam is adapted to intermittently engage roller 60 on the control arm 61 which projects from and is pivotally joined at 62 to the control valve housing 63.

Referring to Figure 4 a pipe fitting 64 is provided at the top of housing 38 to which may be joined a suitable source of compressed air for example, said compressed air being delivered to the cross-fitting or *T* 65 there being a suitable hand valve 66 interposed.

A suitable pressure gauge 67 is joined at 68 to the fitting 65 while a suitable fluid delivery pipe 69 is joined to said fitting at the point 70. The pipe 69 which in this case delivers compressed air, extends downwardly, being joined at 71 to an inlet fitting 72 of the control valve housing 63, said control valve having a compressed air supply pipe 73 as shown in Figure 3.

Referring again to Figure 3 there is diagrammatically shown the work piece ejecting cylinder 74 which is arranged and positioned in longitudinal alignment with the work piece 7, supported upon the work blade 12. Piston 75 is slidably movable within cylinder 74 and has projecting therefrom the piston rod 76 which extends through the outer end of said cylinder and is adapted for operative ejecting engagement with one end of the work piece 7 as shown.

Coiled spring 77 is positioned within said cylinder with its ends respectively bearing against one inner wall of said cylinder and said piston so that when inoperative said piston and piston rod assume the position shown in Figure 3.

The compressed air supply pipe 73 from the control valve 63 is joined at 78 to the right end of cylinder 74 for communication with its interior upon the side of said piston opposite from said coiled spring.

Upon energization of the control valve 63 through intermittent upward pivotal movement of the control arm 61 through operation of cam 58, compressed air is supplied to the pipe 73 for delivery to the interior of the ejecting cylinder 74. The pressure of the compressed air overcomes the force in the spring 77 and the piston 75 is moved to the left forcibly so that the rod 76 operatively bears against and ejects the work piece 7 from its support 12.

As soon as the cam 58 passes the control valve actuating arm 61, the latter returns to the position shown in Figure 3 and the supply of compressed air or other fluid is cut off from the pipe 73, the latter being provided with a suitable exhaust for the escape of the air remaining in said cylinder and pipe once the pressure has been removed. When said pressure has been removed coil spring 77 is effective to effect the return of the piston 75 and its rod to the position shown in Figure 3. In this inoperative position the new work piece 7 may be properly positioned upon the work blade 12 between the grinding wheel 4 and the regulating wheel 11.

Referring now to Figures 2 and 3 the electric motor 55, which drives the control cams 43, 44 and 58, has a mounting bracket 79 which is secured to the mounting plate 80 by the bolts 81. The plate 80 which is substantially rectangular in shape has a pair of supporting arms or bifurcation 82 at its lower end which have transverse openings therethrough for receiving the mounting rod 83.

The rod 83 is supported at its opposite ends 45 within corresponding openings formed in the parallel spaced supports 84 which project rearwardly from the lower end of the housing 38. Consequently the mounting plate 80 is pivotally supported upon the housing 38 by means of the rod 83.

Nut 85 is secured to and projects upwardly from the central top portion of mounting plate 80 and threadably receives therethrough the motor adjusting screw 86. The latter is anchored and retained at its outer end within the guide and support 87 which projects oppositely from a corresponding portion of the housing 38. It will be seen that the mounting plate 80 is thus pivotally adjusted upon the supporting housing 38 and may be adjusted thereon in either a clockwise or counter-clockwise direction for regulating the speed of rotation of the pulley 53.

Pulley 57 is an adjustable type pulley which is split transversely of its axis and has a changeable pulley support i. e. the pulley support being of variable diameter. The adjustable pulley is a standard type whose detail of construction forms no part of the present invention. In operation, however, if the motor 55 is pivoted in a clockwise direction increasing the center distance between pulleys 53 and 57, it is so constructed that said pulley 57 starts to separate with result that the driving diameter thereof is reduced with a consequent reduction in the speed of movement of the pulley belt 54. It likewise follows that if

the motor mounting is pivoted in the opposite direction from such adjusted position, the pulley under the operation of its springs, not shown, tends to move together increasing the driving diameter thereof, to thus increase the speed of movement of the pulley belt 54.

Referring to Figure 3, bolt 32 may be loosened, and the end of link 33 slidably adjusted within slot 34 to thereby determine the extent of the rotary arc imparted to feed nut 23. The greater the arc, the greater will be the amount of the "in" and "out" feeds.

As shown in Figure 2 a hand lever 88 with handle 89 is removably secured to feed nut 23 by a split collar 90 thereon which projects around said nut. This collar is removably secured thereto by the bolt 91.

In the conventional operation of infeed attachments, the hand lever 88 is employed to manually control the in and out movements of the feed carriage. During the period of such manual control the power operated infeed attachment is rendered ineffective by loosening the bolt 28. It follows that to make the infeed adjustment automatic, all that is necessary is to tighten this bolt 28 and at the same time loosen the bolt 91 to render the hand lever 88 ineffective. Consequently it is clear that it is a relatively simple matter to change over from manual control to automatic control.

Having described my invention, reference should now be had to the claims which follow for determining the scope thereof.

I claim:

1. In a grinding machine having an adjustable feed carriage, a stationary lead screw, a reciprocally rotatable feed nut on said screw and retainingly engaged by said carriage for effecting in and out adjustments thereof relative to said lead screw, a longitudinally reciprocal link pivotally and eccentrically joined at one end to said nut for rocking the same on said screw, a reciprocal cross-head joined to the other end of said link, and a pair of coaxial rotatable cams respectively and intermittently engaging opposite ends of said cross-head for effecting reciprocal movements thereof.

2. In combination a stationary lead screw, a feed nut threaded thereon, a reciprocal link pivotally and eccentrically joined at one end to said nut for effecting reciprocal rotary movements thereof, a reciprocal cross-head pivotally joined to the other end of said link, and a pair of coaxial rotatable cams intermittently engaging opposite ends of said cross head for effecting reciprocal movements thereof, whereby said nut is intermittently moved in opposite directions longitudinally of said lead screw.

3. In a grinding machine having an adjustable feed carriage, a stationary lead screw, a reciprocally rotatable feed nut on said screw and retainingly engaged by said carriage for effecting in and out adjustments thereof relative to said lead screw, a reciprocal cross head pivotally and eccentrically joined to said nut for rocking the same on said screw, and a pair of coaxial rotatable cams respectively and intermittently engaging opposite ends of said cross head for effecting reciprocal movements thereof.

4. In a grinding machine having an adjustable

feed carriage, a stationary lead screw, a reciprocally rotatable feed nut on said screw and retainingly engaged by said carriage for effecting in and out adjustments thereof relative to said lead screw, a longitudinally reciprocal link pivotally and eccentrically joined at one end to said nut for rocking the same on said screw, a reciprocal cross head joined to the other end of said link, and a pair of coaxial rotatable cams respectively and intermittently engaging opposite ends of said cross-head for effecting reciprocal movements thereof, said cams being so formed and arranged with respect to each other that there is a lag of the carriage in its infed position to permit grinding of the work piece.

5. In a grinding machine having a work rest and an in and outwardly adjustable work regulating wheel supporting carriage, a pneumatic ejector in axial alignment with the work piece on said work rest and adapted for operative engagement therewith when energized, a stationary lead screw, a reciprocally rotatable feed nut on said screw and retainingly engaged by said carriage for effecting in and out adjustments thereof relative to said lead screw, a longitudinally reciprocal link pivotally and eccentrically joined at one end to said nut for rocking the same on said screw, a reciprocal cross-head joined to the other end of said link, a pair of coaxial rotatable cams respectively and intermittently engaging opposite ends of said cross-head for effecting reciprocal movements thereof, a control valve in communication with said ejector for supplying compressed air thereto energizing the same, and a third coaxial rotatable cam intermittently engageable with said valve for operating the same, said latter cam being so constructed and arranged with respect to said other cams that said ejector will be energized simultaneously with the engagement of one of said other cams effecting out feeding movement of said carriage relative to said work piece.

6. In a grinding machine having an adjustable feed carriage, a stationary lead screw, a reciprocally rotatable feed nut on said screw and retainingly engaged by said carriage for effecting in and out adjustments thereof relative to said lead screw, a longitudinally reciprocal link pivotally and eccentrically joined at one end to said nut for rocking the same on said screw, a reciprocal cross-head joined to the other end of said link, a pair of coaxial rotatable cams respectively and intermittently engaging opposite ends of said cross-head for effecting reciprocal movements thereof, a cam drive shaft on which said cams are secured, and adjustable means for regulating the speed of rotation thereof.

KEITH ANDERSON.
